POLY-ANODE FLIP-FLOP TUBE

Charles R. Williams, Hawthorne, and Chris S. Andersen, Bell, Calif., assignors to Northrop Aircraft, Inc., Hawthorne, Calif., a corporation of California

Application April 16, 1951, Serial No. 221,256

9 Claims. (Cl. 315—167)

1

The present invention relates to multiple electrode cold cathode glow tubes, and more particularly to such a glow tube having two anodes and a single, surface divided, cathode suitable for use as a switch, or flip-flop tube.

Essentially, a flip-flop is a device which has two stable states. The dual anode tube of the present invention has two conducting stable states; either one anode is conducting, or the other anode is conducting. The tube is made to be non-conducting only during relatively short transition times when changing from one state to the other, and sufficient supply voltage is provided to insure re-ignition.

Hagen, in his application, Serial No. 100,178, filed June 20, 1949, has shown, described and claimed a three electrode cold cathode glow tube useful as a switch or flip-flop. This tube has a single, preferably central, anode flanked by two cathodes, immersed in gas at glow discharge pressure. When each cathode is connected to a resistance bridged by a capacity, with these RC circuits connected together, and then through a potential source and a limiting resistor to the single anode, with the source sufficiently high to strike a glow discharge between the anode and one of the cathodes, a negative pulse applied to the anode will cause the glow to momentarily cease. Subsequent refiring forced by the high potential source will occur between the anode and the second cathode leaving the first cathode non-conducting. The RC circuits maintain the "on" to "off" cathode differential voltage during the triggering transition time, and it is this differential which causes the switching action to occur. Output circuits connected to one or both cathodes will indicate this change in tube condition. Such a tube is very useful in counters operating on the binary system.

It might at first appear that the reciprocal of a glow tube of this general Hagen type would operate well. Such a tube would have a single cathode and two anodes, with the RC circuits connected to the anodes and with the polarity of the source reversed. It is a fact, however, that such a reciprocal tube does not operate at all, because the voltage differential necessary to obtain the switching cannot be maintained between the two anodes. The two anodes will conduct simultaneously to the common cathode as a stable condition. When an attempt is made to raise the potential of one anode above the other, the first anode will draw the majority of the cathode current and the glow will creep

2

around the cathode to the side favoring the first anode.

In the present invention suitable anode to anode differential voltage necessary for switching is obtained by dividing the cathode surface into separate areas, one facing and favoring each anode such that for an anode to conduct a substantial current it must strike a glow to its favored area. Conduction from an anode to an unfavored cathode area requires extra anode to cathode potential necessary for the glow path to surmount the obstruction separating the cathode areas, such conduction existing alone would be unstable because of the tendency of the glow to jump to the favored cathode area.

In the present invention, if an anode is conducting a stable current to a glow in its favored cathode area, then a second anode can be raised to and maintained at a potential above that of the first anode without drawing more than a small portion of the glow current. The glow will remain entirely within the first area. Now, if a quenching pulse is applied to the tube, and the voltage differential between the anodes is maintained, the glow will restrike on the second cathode area and the second anode will assume the majority of the glow current. In a circuit which automatically maintains the non-conducting anode at a potential higher than the conducting anode, the glow current can be switched alternately from one anode to the other by a succession of quenching pulses.

It might further appear that two separate gas diodes could be connected at their cathodes to form a dual anode flip-flop circuit. However, in such a circuit it is difficult, if not impossible, to obtain reliable switching action. The conducting bulb will always refire at a lower potential than the non-conducting bulb; hence, the glow will simply return to the same bulb after quenching. Further, it is difficult to keep two separate bulbs matched in their electrical characteristics as aging progressively alters them.

In the present invention all electrodes of the flip-flop are exposed to the same gas and to equal residual ionization after trigger pulse quenching so that with symmetrical construction equal anode to cathode refiring potentials are obtained regardless of which anode was previously conducting. The external circuits need supply only a small and easily self-obtained anode to anode differential voltage to cause the previously non-conducting anode to strike to its cathode section. Also, aging affects both anodes equally so that

the equality in electrical characteristics can be maintained.

It is an object of the present invention to provide a cold cathode glow tube having a single divided area cathode intermediate two anodes that can be operated as a switch or flip-flop tube to transfer conduction from one anode to the other, to provide a usable output pulse, and a usable voltage differential between the anodes.

It is another object of the present invention to provide a three electrode cold cathode glow tube, together with a circuit that will provide for switching the glow discharge in the tube between two anodes and the surface sections of a single cathode.

In brief, the tube of the present invention includes an envelope containing a noble gas at glow discharge pressure and having three or four rod-like electrodes therein, preferably located side by side in a common plane. The center electrode or electrode pair is provided with means for limiting a cathode glow thereon to two glow surfaces thereof, in a more general case three or more, one of these glow surfaces facing one of the lateral electrodes, the other glow surface facing the other lateral electrode.

When used as a switch in a flip-flop circuit, a resistance-capacity circuit is connected to each outer electrode, these circuits being connected together and to the center electrode through a potential source and a current limiting resistance, with the outer electrodes energized positively as anodes, the center electrode energized negatively as a cathode. The source is made sufficiently high in voltage so that a glow discharge is struck between one anode and the cathode glow surface facing the conducting anode. Upon application of a positive pulse to the cathode, the already established glow will cease, and the glow will be re-established between the other cathode glow surface and the other anode. The glow limiting means prevents the glow from travelling from one side of the cathode to the other, unless a discontinuous or switching action occurs.

The present invention will be more fully understood by reference to the drawings in which:

Figure 1 is a perspective view, the envelope being cut away, of a tube embodying the present invention.

Figure 1a is a perspective view of another form of cathode for the tube of Figure 1.

Figure 2 is a circuit diagram of the tube of Figure 1 in use as a switch or flip-flop.

Referring to Figure 1, an envelope 1 is provided with a re-entrant stem 2 sealed to one end thereof, stem 2 having three leads 3, 4 and 5 sealed at a pinch 6 therethrough. The inner ends of leads 3, 4 and 5 extend beyond the pinch 6 to form a central cathode 8 and lateral anodes 9 and 10. Cathode 8 is divided as by a saw cut 11, this cut being filled with an insulating plate 12 made of glass, mica or ceramic, for example. Plate 12 extends at right angles to the common plane of the cathode and anodes. It is preferred that plate 12 divide the cathode into two glow surfaces 14 and 15, one facing each anode and placed so that no surface of the cathode is exposed completely around the cathode.

The envelope is evacuated according to standard practice and filled with neon, for example, at glow discharge pressure, i.e., from 100 mm. of mercury pressure to one-half atmosphere pressure, for example. A trace of polyatomic gas may be added to decrease deionization time and to promote triggering.

The tube of Figure 1 can be used as a flip-flop in the circuit shown in Figure 2, for example.

Here, each anode 9 and 10 is connected to ground through a resistance 20 bridged by a capacity 21, both RC circuits preferably being alike. Cathode lead 4 is connected through a current limiting resistance 22 to the negative pole 23 of a potential source 24, the positive pole 25 thereof being grounded.

An input circuit 26 is connected to cathode lead 4 and an output circuit, such as an output circuit 27, can be connected to either or both anodes.

In operation, the potential of source 24 is sufficiently high for a glow discharge to strike between one of the anodes and the nearest cathode face. Upon the application of a positive pulse P to the cathode through input line 26, the glow is extinguished, and automatically restruck between the other cathode face and the other anode. An output pulse is thus provided in each output circuit 27.

If the surface of cathode 8 were not to be divided into two parts, the two anodes would share the cathode current equally and they would remain at substantially equal potentials and lack the voltage differential necessary for switching. The tube is then inoperative as a switch. When, however, the glow on the cathode surface facing the struck anode is prevented from spreading to the opposite side of the cathode, the side facing the idle anode as by the use of shield 12, a positive input pulse will cause the original glow discharge to cease entirely and then to be re-established on the opposite surface facing the other anode. Additional pulses will then switch the discharge from one anode to the other in the desired flip-flop fashion.

While we prefer to split the cathode and insert a shield therein to separate the surfaces facing the two anodes, the glow can be prevented from spreading from one side of the cathode to the other in several other manners. For example, the cathode surfaces facing the two anodes can be isolated by a dividing line 30 of non-conducting material such as insulating paint or ceramic as shown in Figure 1a. The cathode can also be formed of two electrically connected but spaced wires (as shown diagrammatically in Figure 2) with or without a shield between. In any event, the main desideratum is some means to prevent the cathode glow from spreading from one side or the other thereof without a break in current.

The tube of the present invention operates with positive input pulses as contrasted with the negative input pulses required to be placed on the single anode of the Hagen tube in the application cited above. For this reason, the tube finds good use, alone or in combination with the Hagen type tube, in binary counters depending upon flip-flop action for operation.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute, the invention has been described in language more or less specific as to structural features, it is to be understood that the invention is not limited to the specific features shown, but that the means and construction herein disclosed comprise a pre-

ferred form of putting the invention into effect, and the invention is, therefore, claimed in any of its forms or modifications within the legitimate and valid scope of the appended claims.

What is claimed is:

1. A cold cathode glow tube comprising an envelope containing a filling of gas at glow discharge pressure, a pair of anodes and means providing electrically continuous cold cathode surfaces positioned between said anodes, said electrodes being in a common plane, said surfaces of said cathode being separated into separate cathode glow areas, with a cathode glow area facing each anode.

2. A cold cathode glow tube comprising an envelope containing a filling of gas at glow discharge pressure, a pair of anodes and a cold cathode positioned between said anodes, said electrodes being in a common plane, and glow preventing means separating the surface of said cathode into separate cathode glow areas, with a cathode glow area facing each anode.

3. Apparatus in accordance with claim 2 wherein said glow preventing means is a coating of insulating paint on said cathode.

4. Apparatus in accordance with claim 2 wherein said cathode is divided in a plane at right angles to the plane of said electrodes, and wherein an insulating shield is positioned between the divided portions of said cathode.

5. Apparatus in accordance with claim 2 wherein said cathode is divided in a plane at right angles to the plane of said electrodes, and wherein an insulating shield is positioned between the divided portions of said cathode, and wherein said shield extends outwardly beyond the extent of said cathode in directions at right angles to the plane of said electrodes.

6. The tube of claim 1 in combination with a circuit for causing a glow discharge between one anode and the facing cathode glow area, and means for applying an input pulse to said

cathode to switch said discharge to the other of said anodes and the other of said glow areas.

7. A cold cathode glow tube consisting of an envelope containing a filling of gas at glow discharge pressure, a pair of anodes sealed within said envelope and having separate electrical leads therefor, and means providing electrically continuous cold cathode surfaces sealed within said envelope between said anodes and having a common electrical lead therefor, said surfaces of said cathode being separated into separate cathode glow areas within said envelope, with a cathode glow area facing each anode, whereby a glow discharge between one anode and its facing cathode area will not effect a glow on the other cathode area.

8. A bi-stable flip-flop circuit comprising a cold cathode glow tube having an envelope containing a filling of gas at glow discharge pressure, a pair of anodes and a cold cathode positioned between said anodes, glow preventing means separating said cathode into separate cathode glow areas within said envelope, with a cathode glow area facing each anode, means for striking a glow between one anode and the facing cathode glow area, means for maintaining a potential difference between the active and inactive anode, and means for applying a positive input pulse to said cathode to switch said glow between the other of said anodes and the other of said cathode areas.

9. Apparatus in accordance with claim 8 including output circuit means connected to each of said anodes.
